UNITED STATES PATENT OFFICE.

KARL SCOTTI, OF FRANKFORT-ON-THE-MAIN, GERMANY.

LIQUID-METER.

No. 818,566.

Specification of Letters Patent.

Patented April 24, 1906.

Application filed June 26, 1903. Serial No. 163,269.

To all whom it may concern:

Be it known that I, KARL SCOTTI, a subject of the Grand Duke of Hesse, residing at Frankfort-on-the-Main, Germany, have invented certain new and useful Improvements in Liquid-Meters, of which the following is a specification.

This invention has for its object an improved fluid-meter.

10 The invention is illustrated in the accompanying drawings, in which—

Figures 1 and 1^a illustrate by plan and elevation one form of the invention. Figs. 2 and 2^a illustrate by plan and section a modification having circuit-closing means. Figs. 3 and 3^a are like views of a further modification. Figs. 4 and 4^a are like views of still another modification. Figs. 5 and 6 are elevations taken at right angles to each other, 20 showing further modifications.

In a circular groove *a*, Fig. 1, a body *b* (for instance a ball) is freely movably arranged. The liquid passes through a tangential inlet-passage *c* into the groove or channel *a* and leaves the same again through a discharge-channel *d*, thus causing the whole of the liquid contained in the channel to be rotated and carry the body *b* with it. The movement of this body produced by the flow of 25 the liquid may be transmitted by electrical or mechanical means to an indicating mechanism.

In the case of electric transmission the closing and breaking of the circuit may be 30 produced by the body running at a given place onto a circular wire *e*, fastened at *e'*, Fig. 2, at an inclination to the track of the body *b*, and the elastic part *f* of the same depressing during a given time a tread by which at *g* in 35 any suitable manner a circuit is closed. After the body *b* has passed the place *f* the elastic part *f* of the circular wire *e* again rises and breaks the circuit at *g*.

Another method of closing and opening the 40 circuit in electric transmission is shown in Fig. 3. This rests on the utilization of the great cohesion of mercury. Mercury contacts *h i* project into the running-groove *a* and are isolated from each other and from the casing. These contacts are so close together 45 that as the body *b* passes over them it will be in contact with both simultaneously, and thus the circuit is closed.

Fig. 4 shows as an example a form of construction for mechanical transmission of the 50 movement of the free body *b* to a counting

mechanism. A ball or sphere *b*, freely rolling in a groove *a*, here at each revolution strikes once against a fly-wheel or wing-wheel *k*, rotating on *l*, and turns the same one division 55 forward, which rotation is transmitted to a counting mechanism. The inlet and outlet of the liquid may take place at any suitable point, (above or beneath or at the side,) and several passages may also be arranged. The 60 meter may also be protected against frost in the following manner: The casing with the channel *a*, Fig. 1, consists of two parts *m* and *n*, which are held together by screws *o*. Springs *p* of any suitable construction are located beneath these screws. These springs under normal conditions press together the two parts of the casing and form a tight 65 joint; but as soon as the water freezes in the channel *a* the two parts of the casing *m* and *n* 70 separate in consequence of the expanding ice as the springs *p* yield to the strong pressure. When the ice melts again, these springs *p* draw the parts *m* and *n* again firmly together, so that a tight joint is insured. 75

1 is an electromagnet whose armature 2 is secured to the rod 3 passing through the electromagnets. The rod and armature-plate are raised from the magnets by the spring 4. Thereby the lift is limited by the set-screw 5 80 and varied as needed by turning the same. On the upper end of the rod 3 a chain 6 is attached, which runs over a disk 7, of hard rubber or the like, and is secured to a spring 8, the tension of which can be regulated by moving 85 the pin 9. Connected to the disk 7 is the drum 10, on the extension 11 of which the hard-rubber disk is mounted. This extension is provided with a flange 12, over which the finger 14, journaled in a fork 13, engages. 90 The slot of the finger is somewhat wider than the flange 12 of the extension 11; but the edges are obliquely placed, and the finger is always held in an oblique position by the spring 15, so that it prevents movement of 95 the drum in one direction, since it lies against the fork 13 and only permits movement in the other direction. The rotation of the drum is transmitted by the gear 16 to the spring number-disks 18, arranged in a casing 100 17, which disks are driven in the usual way by the gears 19. The current for the electromagnets goes from the battery 20 to the casing of the water-meter and is then led through an insulating-sleeve to the pin 21, 105 which stands under the pressure of the spring *f*. By pressing down the pin by the rolling

thereover of the ball the circuit is closed, which leaves the casing through the binding-screw 22 and returns through the electro-magnets 1 to the battery 20. When the circuit is closed, the armature is attracted and the chain is thereby drawn, and thereby the numbering mechanism is set in motion. When the current is broken, the spring 4 raises the armature, and the chain, which is held taut by the spring 8, slides over the hard-rubber roller, which, held by the finger 14, does not take part in the rotation. At each closing of the circuit a rotation of the numbering mechanism in one direction takes place, so that the number of rotations of the ball, and therewith the quantity of water, can be read off the numbering mechanism. Since the regulating-screw 5 permits wide variation in the lift, one size of indicating mechanism can be employed for all sizes of water-meters, it being then only necessary to change the position of the screw for each.

What I claim, and desire to secure by Letters Patent of the United States, is—

1. A liquid-meter consisting of a casing with an annular channel having entrance and exit passages tangentially arranged adjacent to each other, a body in said channel, said body being freely and continuously driven forwardly in said channel by the pressure of the water, and of a measuring mechanism

which is operated by said body at each revolution.

2. A liquid-meter consisting of a casing with an annular channel having entrance and exit openings tangentially arranged adjacent to each other, a body in said channel, said body being freely and continuously driven forward in the channel by the pressure of the water, and a measuring mechanism comprising a spring lying in the channel, which is pressed downwardly by the said moving body, a contact connected with the spring, a circuit controlled by the contact, and a registering mechanism in the circuit, substantially as described. 35

3. A fluid-meter comprising a casing having an endless raceway therein, an entrance to said raceway and an exit therefrom for the moving fluid, a body freely and continuously movable by the fluid current throughout said raceway, a movable circuit-closing device projecting in said raceway in the path of the movable body, a circuit, and an indicator in said circuit substantially as described. 40

In testimony whereof I have hereunto set my hand in the presence of two witnesses.

KARL SCOTTI. 55
